UNITED STATES PATENT OFFICE.

ALBERT COHN, OF CHICAGO, ILLINOIS.

DESIGN FOR A MUSICAL TOY OR KAZOO.

52,471.

Specification for Design.

Patented Sept. 24, 1918.

Application filed November 28, 1917. Serial No. 204,471. Term of patent 14 years.

To all whom it may concern:

Be it known that I, ALBERT COHN, a citizen of the United States, residing at Chicago, in the county of Cook and State of Illinois, have invented a new, original, and ornamental Design for a Musical Toy or Kazoo, of which the following is a specification, reference being had to the accompanying drawing, forming part hereof.

The figure is a perspective view of a musical toy or "kazoo," showing my new design.

I claim:

The ornamental design for a musical toy or "kazoo," as shown.

ALBERT COHN.
